TRAY FOR ELECTRONIC COMPONENTS OR THE LIKE

Thomas M. Britt, Red Bank, N.J., assignor to Lily-Tulip
Cup Corporation, New York, N.Y., a corporation of
Delaware

Filed Nov. 27, 1968, Ser. No. 14,703

Term of patent 14 years

Int. Cl. D9—04; D15—99
U.S. Cl. D9—185

FIG. 1

FIG. 2

FIG. 3

FIG. 4

FIG. 5

FIG. 6

FIG. 7

FIGURE 1 is a top plan view of a tray for electronic components or the like, showing my new design.

FIGURE 2 is an elevation as seen in the direction of line 2—2 of FIGURE 1.

FIGURE 3 is an elevation as seen in the direction of line 3—3 of FIGURE 1.

FIGURE 4 is an end elevation as seen in the direction of line 4—4 of FIGURE 1.

FIGURE 5 is a cross-sectional view taken along line 5—5 of FIGURE 1; and

FIGURE 6 is a cross-sectional view taken along line 6—6 of FIGURE 1.

FIGURE 7 is a top perspective view for a tray of electronic components or the like.

I claim:

The ornamental design for a tray for electronic components or the like, substantially as shown.
